(57) **CLAIM**

The ornamental design for a shoe sole, as shown and described.

DESCRIPTION

FIG. 1 is a plan view of a shoe sole embodying my new design;

FIG. 2 is a left side elevational view thereof;

FIG. 3 is a front elevational view thereof;

FIG. 4 is a right side elevational view thereof;

FIG. 5 is a rear perspective view thereof;

FIG. 6 is a cross-sectional view taken along line 6—6 of FIG. 1;

FIG. 7 is a cross-sectional view taken along line 7—7 of FIG. 1; and,

FIG. 8 is a cross-sectional view taken along line 8—8 of FIG. 1.

The elements shown in broken lines in the drawings depict portions of the shoe sole that form no part of the claimed design.
